UNITED STATES PATENT OFFICE.

RAYMOND M. MALONE, OF MILWAUKEE, WISCONSIN.

DUMPING APPARATUS.

Application filed May 31, 1921. Serial No. 473,840.

To all whom it may concern:

Be it known that I, RAYMOND M. MALONE, a citizen of the United States, residing at Milwaukee, in the county of Milwaukee and 5 State of Wisconsin, have invented certain new and useful Improvements in Dumping Apparatus, of which the following is a specification, reference being had to the accompanying drawing, forming a part thereof.

10 This invention relates to dumping apparatus for the bodies of motor trucks and the like and the object of the invention is to improve the construction and operation of dumping apparatus in the manner to be 15 hereinafter described and claimed.

Referring to the drawings, which accompany this specification and form a part hereof, which drawings illustrate an embodiment of this invention, and on which drawings the same reference characters are employed to designate the same parts wherever they may appear in the several views, Fig. 20 1 is an elevation of part of a motor truck, parts being shown as broken away and 25 parts being shown in section; Fig. 2 is a plan view of parts of the motor truck; Fig. 3 is a plan view, with parts broken away and parts shown in section, of the engine and associated mechanism; Fig. 4 is a vertical section, taken on the line 4—4 on Fig. 3, looking in the direction indicated by the arrows; and Fig. 5 is an elevation of details of construction. Figs. 3, 4 and 5 of the drawings are drawn to a larger scale than 30 Figs. 1 and 2.

Referring to the drawings, the reference numeral 1 designates the chassis which is provided with the engine 2, the gear box 3, and the propeller shaft 4 for driving the 40 wheels 5. The body 6 is pivotally supported by the chassis near its rear end in any suitable or preferred manner as, for example, by a pin 7 which passes through the brackets 8 and 9, one of which is secured to 45 the chassis 1 while the other is secured to the body 6. It is preferred to have a pair of brackets 8 and 9 and a pin 7 at each side of the truck. The forward or front end of the body 6 may rest upon any suitable support 50 10, when the body 6 is in a substantially horizontal position.

A transverse shaft 11 is supported by the chassis 1 and is provided with cranks 12 secured near the ends thereof and these

cranks are connected with links 13 which 55 incline upwardly and forward when the body is in its lowermost position. Each link 13 is illustrated as composed of a pair of members which embrace a crank 12 and which are connected by lost motion connections with the body 6. In the specific construction illustrated, lugs 14 are secured to the body 6 and are provided with pins 15 which pass into or through slots 16 in the members of each link 13. It will be clear 60 from the foregoing description that the body 6 can be raised by rotating the transverse shaft 11. Gear segments 17 are secured to the transverse shaft 11 and mesh with pinions 18 secured to a shaft 19. A 70 large gear 20 is secured to the shaft 19 and meshes with a pinion 21 which is secured to a shaft 22. The shaft 22 also has a worm wheel 23 secured thereto with which a suitably supported worm 24 meshes. The 75 shafts 19 and 22 are journaled in supports 25 and 26 which are supported by the shaft 11 at their rear ends and by the transverse member 27 at their front ends. The journal bearings 28 and 29 for the transverse 80 shaft 11 may be secured to the side bars of the chassis frame so that the dumping apparatus can be readily assembled with any construction of motor truck.

The engine 2 is illustrated as a common 85 type of internal combustion engine which turns over only in one direction and from which power is supplied by a clutch (not shown) to a clutch shaft 30. The gear box 3 may contain any of the common types of 90 gear mechanism for securing changes of speed and reversal of direction of motion of the motor truck and this mechanism requires no description in this specification other than to say that the gear 31 is secured to the clutch shaft 30 and meshes with a gear 32 secured to a lay shaft 33. With such a construction, when the engine is turning over or running, the gears 31 and 32 will be rotated and their direction of rotation 95 will never be reversed. I attach a secondary gear box 34 to the truck, preferably by fastening it to the gear box 3, which has been provided with an aperture 35 so that the gear 36 can mesh with the gear 32. 100 The gear 36 is suitably supported by the secondary gear box 34 in any manner so that it can rotate but be kept constantly in mesh 105

with the gear 32. The drawings show the gear 36 as rotatably supported upon a non-rotatable stud 37. A shaft 38 is rotatably mounted in the secondary gear box 34 and 5 a double slidable gear 39 is splined thereto or otherwise suitably connected therewith to rotate the shaft 38 while being free to be moved longitudinally thereon. The double slidable gear 39 has a large gear part 40, 10 a smaller gear part 41, and a circumferential groove 42 for a shifting fork 43. A reversing gear 44 is loosely supported upon a stud 45, which is immovably fixed in the secondary gear box 34, and is always re- 15 tained in mesh with the smaller gear part 41 of the double slidable gear 39. In the specific construction illustrated by the drawings, the shifting fork 43, besides engaging in the circumferential groove 42 of the 20 double slidable gear 39, engages in a circumferential groove 46 in the hub 47 of the reversing gear 44 so that a movement of the shifting fork 43 by a movement of the shifting rod 48 will move simultaneously the 25 double slidable gear 39 and the reversing gear 44. The arrangement and proportion of parts is such that either the large gear part 40 of the double slidable gear 39 or the reversing gear 44 can be brought into 30 mesh with the gear 36 by movements of the shifting rod 48 and the extent of movement required to effect this shift of gears is great enough to entirely disengage the large gear part 40 from the gear 36 before the re- 35 versing gear 44 can be engaged with gear 36 or vice versa, so that the double slidable gear 39 (and the reversing gear 44) can be moved to a neutral or inoperative position, as clearly shown by Fig. 3 of the drawings. 40 The shaft 38 is connected with the worm 24 in any suitable manner as, for example, by a shaft 49 and universal couplings 50 and 51.

The shifting rod 48 is moved automatically to move the large gear part 40 of 45 the double slidable gear 39 or the reversing gear 44 out of mesh from the gear 36 by a crank arm 52 which is loosely supported on the transverse shaft 11 and which is connected with the shifting rod 48 by a rod 53, 50 bell-crank lever 54 and a link 55. The crank arm 52 is provided with a hub 56 which has a part recessed to provide two shoulders 57 and 58 for a projection 59 to contact with to rotate the crank arm 52 and 55 move the shifting rod 48 to disengage either the large gear part 40 or the reversing gear 44 from the gear 36 to stop further movement of the body 6. The projection 59 may be formed on a collar 60 which may be se- 60 cured to the transverse shaft 11 by a set screw 61. The angular distance between the shoulders 57 and 58 should be the same as the required angular rotation of the trans- 65 verse shaft 11 plus the angle subtended by the projection 59. After the crank arm 52

has been moved by the projection 59 to move the shifting fork 43 and the gears 40, 41 and 44 into inoperative positions with respect to the gear 36, as hereinbefore described, the body 6 can be moved in the opposite direction by pulling up or pushing down, as the case may be, on the handle 62 which is connected to the bell-crank lever 54. This will be obvious from an inspection of Fig. 5 of the drawings which shows 75 the parts in the positions occupied after the projection 59 has contacted with the shoulder 57 and moved the lower end of the crank arm 52 to the right which has brought the slidable gear 39, and the reversing gear 80 44, into the inoperative or stop positions. It is obvious that the crank arm 52 may be moved still further to the right without encountering resistance. It is also obvious that, when the transverse shaft 11 has been 85 rotated to such an extent that the projection 59 has contacted with the shoulder 58 and moved the crank arm 52 to the left to stop the further rotation of the transverse shaft 11, the crank arm 52 can be moved to 90 the left without encountering resistance. In other words, the function of the projection 59 is to move the shifting rod 48 in such a direction that the large gear part 40 will be moved away from the gear 95 36 and the reversing gear 44 will be moved towards the gear 36, or vice versa, and the function of the handle 62 is to complete the extent of movement required, when desired, to move the body 6 in the direction 100 opposite to the direction in which it moved last.

The lost motion connections between the links 13 and the body 6 are important features of construction and the extent of movement permitted by this construction should be sufficient to enable the pinions 18 to run out of mesh with the teeth of the gear segments 17 when the gear segments are being turned in either direction. This construction prevents serious damage in case the projection 59, for example, should be broken off so that the movement of the body 6 would not be automatically stopped as it will be seen from an inspection of Fig. 1 of the 115 drawings that a continued rotation of the pinion 18 in a clock-wise direction will simply rotate the gear segment 17 out of mesh, the support or stop 10 holding the body 6 in a fixed position while the link 13 moves down on the pin 15 and the pinion 18 can continue to rotate indefinitely without any damage being done. If the pinion 18 is being rotated counter-clock-wise, the projection 59 being broken off for example, 120 the gear segment 17 will be run out of mesh with the pinion 18 and the adjustable, screw stop 63 will engage under the support 26 to prevent further rotation of the gear segment. In this case the gear segment 17 can 130

be reengaged with the pinion 18 by pulling the body 6 down or rotating the transverse shaft 11 in any convenient manner while in the former case the rotation of the shaft 11 to reengage the gear segment 17 with the pinion 18 is effected in any convenient manner. While in the foregoing explanation only the gear segment 17 and the pinion 18 shown by Fig. 1 of the drawings have been referred to for convenience of explanation, it will be understood that both gear segments 17 can run out of mesh with their respective pinions 18. The use of two gear segments 17 and two pinions 18 located near opposite sides of the truck is to prevent twisting strains being set up when the body 6 is being elevated.

The lost motion connections between the body 6 and the elevating mechanism also permits the body 6 to be moved and jarred to dislodge material which may tend to stick to it. If the rear of the body 6 projects some distance rearwardly of the pin 7, the material sliding from the body will tip the front end of the body up and the pins 15 will be stopped suddenly by contacting with the upper ends of the slots 16, thus jarring the body 6, or the body can be swung back and forth as far as permitted by the slots 16 and be jarred each time the pins contact with the ends of the slots.

The operation of the apparatus will be readily understood from the foregoing description. By manipulation of the handle 35 62 either the gear 40 or the reversing gear 44 can be engaged or meshed with the gear 36 and the body 6 can be raised or lowered. The raising or lowering of the body 6 will be automatically stopped by the crank arm 40 52 and, if not stopped the pinions 18 will

simply run the segment gears 17 out of mesh so that parts will not be broken.

The apparatus as a whole can be assembled with any truck and by describing and illustrating specific constructions I do not intend 45 to limit my invention to the precise construction and arrangement of parts shown as the specific constructions and arrangements can be varied more or less.

The gear segments 17 and their pinions 18 can be enclosed or protected by any suitable or preferred guards or casings (not shown) and the gear 20 and its pinion 21 can be likewise enclosed or protected by a guard or casing (not shown) to prevent 55 small stones or other material from being caught between the gears and the pinions.

What is claimed is:

The combination with a motor truck provided with a tiltable body, a non-reversible 60 engine and means for reversing the direction of motion of the motor truck, of separate reversible mechanism, a pinion adapted to be rotated by the separate reversible mechanism, a gear segment adapted to mesh 65 with said pinion and to be run out of mesh therewith, means for tilting the truck body by movements of said gear segment, a stop for arresting further movement of said gear segment after it has been run out of mesh 70 with said pinion, manually operable means for controlling the operation of said separate reversible mechanism, mechanical means for controlling the operation of said separate reversible mechanism, and a connection 75 between the said manually operable means and the mechanical means.

In witness whereof I hereto affix my signature.

RAYMOND M. MALONE.
